DESIGN FOR A COMBINED STAND, ELECTRIC HEATER AND FAN

John T. Rausch and George Towne, Danville, Ill.

Application November 2, 1946, Serial No. 134,478

Term of patent 14 years

(Cl. D81—10)

To all whom it may concern:

Be it known that we, John T. Rausch and George Towne, citizens of the United States, residing at Danville, in the county of Vermilion and State of Illinois, have invented a new, original, and ornamental Design for a Combined Stand, Electric Heater and Fan, of which the following is a specification, reference being had to accompanying drawing, forming a part thereof. Figure 1 is a perspective view of a combined stand, electric heater and fan, showing our new design. Figure 2 is a top plan view thereof.

The characteristic features of our design reside in the portions shown by means of full lines in the drawing.

We claim:

The ornamental design for a combined stand, electric heater and fan as shown and described.

JOHN T. RAUSCH.
GEORGE TOWNE.
